UNITED STATES PATENT OFFICE

BERNARD DUCHSCHER, OF CLEVELAND, OHIO

METAL REINFORCEMENT FOR STRUCTURAL REINFORCED CONCRETE MEMBERS

Application filed October 24, 1929. Serial No. 402,241.

My invention relates to improvements in metal reinforcements for concrete supports, more particularly to reinforcements for concrete supports used in constructions, and it consists in the combinations, constructions and arrangements herein described and claimed.

An object of my invention is to provide a metal reinforcement that is especially suitable for reinforced concrete load-carriers requiring great resisting moments, as well as great resisting shears of force in their design.

A further object of my invention is to provide a metal reinforcement for concrete that may be adapted to relieve the concrete in which it is embedded of tensile, flexural and shearing stresses and strains with the use of a minimum amount of metal reinforcement.

A further object of my invention is to provide a metal reinforcement portions of which may be positioned adjustably before the embedding process in the most effective position for relieving the concrete of the various strains and stresses.

A further object of my invention is to design a metal reinforcement that may be extended to reinforce a concrete member of any desired volume.

A further object of my invention is to provide a device of the type described which is simple in construction, has few parts and is not likely to get out of order easily.

Other objects and advantages will appear in the following specification, and the novel features of the invention will be particularly pointed out in the appended claims.

My invention is illustrated in the accompanying drawings, forming a part of this application, in which

Figure 1 is a top plan view of one form of my device assembled for use,

Figure 2 is a side elevational view of the same form of my device,

Figure 3 is a sectional view on line 3—3 of Figure 1 looking in the direction of the arrow,

Figure 4 is a sectional view on the line 4—4 of Figure 1 also looking in the direction of the arrow,

Figure 5 is a perspective detail view of a portion of my device,

Figure 6 is a sectional view showing my device fitted to apply as a reinforcement to a concrete member of small volume,

Figure 7 is a plan view of another form of my device,

Figure 8 is an elevational detail view of a portion of my device,

Figure 9 is a sectional view on the line 9—9 of Figure 7,

Figure 10 is a sectional view on the line 10—10 of Figure 7, and

Figure 11 is a perspective detail view of a portion of my device.

In carrying out my invention I make use of metal bars, termed bulb bars, as shown at 1. These bulb bars comprise a bulb-shaped portion shown at 2, a reduced portion as at 3 and lugs 4 positioned in paired relation along said reduced portions for the purpose of securing locking web members 5 thereto.

These web members 5 by being wedged at those portions 6 thereof between the lugs 4 and the bulb portions 2 of the bulb bars 1 are held in rigid position relative thereto, in securing which effect the portions 6 of the webs 5 are bent slightly, as is readily seen from an examination of Figure 3. These webs fixedly position the bulb bars in parallel relation relative to one another and prevent lateral movement thereof. It is easily seen that this system of reinforcement could be extended to reinforce a concrete member of any extent by simply increasing the number of bulb bars and providing a correspondingly extending web.

As is also shown in Figure 3 these webs 5 are provided with elongated openings 7, adapted to accommodate therein the concrete in which they are embedded. These web members are adapted to be bent along the dotted line 1—1, as shown in Figures 3 and 10, to any desired angle for a purpose which will presently appear.

For preventing longitudinal movement of the bulb bars, as well as for the securing of said bulb bars against lateral movement, I provide locking yokes 8 provided with downwardly extending flange portions 9 and 10

adapted to engage between the lugs 4 on the inside and the outside of said bulb bars respectively. These flanges 9 and 10 are fastened to the bulb bars by the insertion of any suitable expanding means in web shaped slots shown at 11.

From the foregoing description of the various parts of the device the use, thereof, will be readily understood. This metal reinforcement is designed especially for shallow beams and heavy floor slabs wherein the reenforcement must resist deformation by flexural tension by relieving the concrete of tensile stresses and strains. The sectional area of the bulb in addition to the upper short stem, above the bulb and the webs, is made large enough to resist the greatest tensile stresses required. The webs 5 are bent about the line 1—1 with varying slopes, approximating the lines of the principle stresses and supporting the flexural tensile stresses with the flexural shearing stresses at various diagonal section of the load carrying concrete member. These web plates may also be spaced along the bars as desired for the accommodation of various stresses occurring at various points.

The yokes, for the securing of my bulb bars against lateral movement, as well as against longitudinal movement, are placed upon the bulb bars and suitably spread in locking relation. It is readily apparent that by the use of a desired number of bulb bars and the extension of the webs and yokes to accommodate said bulb bars as desired, I may structurally reenforce a concrete member of any size, although the use of a single bulb bar unit and a double bulb bar unit only are shown in my drawings. The slots 7 in the web and the irregular formation of the bulb bars and yokes furnish excellent means for engaging the concrete in which the structure is to be embedded.

Figure 7 shows an adaptation of my device which is especially designed for deep beams, girders, arches, ribs and similar concrete structures. The bulb bars 12 are constructed exactly similar to the bulb bars 1 with the exception that the upper and reduced portion are extended into vertical upstanding flanges. These upstanding flanges or stems are provided with oppositely disposed perforations 13 which in company with the lugs 4 on these bulb bars provide a continuous bond between said bars and the concrete embedding them, said bond being simultaneously, a frictional and mechanical bond. This long stem bulb bar is designed to resist the deformation of a reinforced concrete load-carrier not only by a horizontal tension but also by a flexural shear, entirely bearing the tensile, as well as the shearing stresses and strains in the concrete embedding said bulb bar. The cross-sectional area 2 of this bulb bar is made of

sufficient area to support its proportionate share of the largest tensile stresses while the perforated stem extending above the bulb portion is made of sufficient sectional area to carry its proportion of the greatest shearing stresses as required in such load carriers, for which this long stem bulb bar is especially suited.

This perforated stem extends into the compression area of the concrete member. As a result, said bar, assists the concrete in supporting the elastic action of the load carrier in a manner similar to that obtained in homogeneous load carriers made of the same elastic material throughout. The web plates 14 are constructed similarly to web plates 5 except that they provide long and short slots 15 and 16, while that portion 17 of said webs may be perforated or unperforated as the case requires. These webs may also be bent as in the case of webs 5. The purpose of these webs is to release the tensile, as well as the shearing stresses and strains in the concrete portions comprised by the bulb bars and also in the bulb bars and the protective coats of concrete in the load carrier.

The yokes 18 are of a little different construction than the yokes 8 in that they are not provided with flanges for engaging the outer portion of the bulb bar. These yokes, however, suitably secure the bars in spaced parallel relation.

The use of this device is similar to that of the device consisting of the bulb bars which do not have the upstanding stem. The various parts are assembled as before, the webs being bent to the desired angle and the elements being constructed of the cross section desired. The perforations 13 and the lugs as in the former case provide excellent gripping surfaces for engagement with the embedding concrete. The structure is formed and adapted to be positioned to bear the stresses and strains which tend to flexurally shear and tension the load supporting concrete member.

Due to the locking arrangement of all the parts of my device, the elastic expansion and contraction due to the action of imposed loads and temperature changes is equalized in all sections of the load carrier so that the concrete, embedding my reenforcement, is released of the function of equalizing internal stresses and strains in the load carrier.

I claim:—

1. A metal reenforcement for concrete, comprising a plurality of bars adapted to relieve the concrete of tensile and shearing stresses and strains, means for securing said bars against transverse and longitudinal movement relative to one another and further means for securing said bars in spaced parallel relation, said securing means and said bars being formed with inter-engaging means.

for variably positioning said securing means along the length of said bars.

2. A metal structure for reenforcing concrete comprising a plurality of bars for resisting the tensile and shearing stresses and strains and web means for securing said bars in spaced parallel relation and further resisting the tensile and shearing stresses and strains, said web means being provided with openings adapted to extend into the compression portions of the concrete, whereby a strong bond is formed between the webs and said concrete, and the expansion and contractions of the concrete due to temperature and load changes is provided.

3. A metal reenforcement for concrete comprising a bar composed of a body portion having a reduced portion extending outwardly along one longitudinal edge thereof, and lugs projecting in paired relation from opposite sides of the reduced portion defining interlocking means for other reenforcing members.

4. A metal reenforcement for concrete comprising a bar composed of a body portion and a reduced portion extending therefrom, spaced lugs projecting in opposed relation from the sides of the reduced portion and a web member having a slot for loose engagement upon the bar between the lugs and adapted for movement longitudinally of the bar into interlocking engagement with said lugs.

5. A metal reenforcement for concrete comprising a pair of bars each formed with a projecting reduced portion, spaced lugs extending from the reduced portions, and a locking yoke formed with flanges for engagement between the lugs to maintain the bars in spaced parallel relation.

6. A metal reenforcing structure for concrete comprising a pair of bars each formed at spaced points with oppositely extending lugs, a web member maintained in interlocking engagement with the bars by engagement with certain of the lugs and a locking yoke engaging the bars intermediate the lugs and maintaining the bars in spaced parallel relation.

BERNARD DUCHSCHER.
